UNITED STATES PATENT OFFICE.

JOHN F. APPLEBY, OF MINNEAPOLIS, MINNESOTA, ASSIGNOR TO THE
MINNEAPOLIS HARVESTER WORKS, OF SAME PLACE.

HARVESTER.

SPECIFICATION forming part of Letters Patent No. 324,350, dated August 18, 1885.

Application filed November 25, 1884. (No model.)

To all whom it may concern:

Be it known that I, JOHN F. APPLEBY, of Minneapolis, Minnesota, have invented a certain Improvement in Harvesters, of which 5 the following is a specification.

My improvement relates to the metallic yokes which are cast or otherwise formed in one piece with the rack-standards bolted to the frames of harvesters, and which are employed for preserving the engagement of the gear of the drive-wheel with the pinion on the counter-shaft, through which power is transmitted from the drive-wheel. The yoke for this purpose is hung over the box which affords the bearing for the end of the counter-shaft upon which the pinion is mounted; and my invention consists in the insertion through the bight of the yoke of an adjusting screw-bolt provided with suitable jam-nuts and 20 adapted to bear upon the exterior of the box in which the counter-shaft is journaled, and thereby affording a means for accurately adjusting and permanently maintaining the distance between the center of the counter-shaft 25 and the curved rack which engages the windlass-gear affixed to the axle upon which the drive-wheel turns.

In the accompanying drawings, illustrating my invention, Figure 1 is an elevation of the metallic rack-standard and yoke, showing in 30 transverse section the counter-shaft and the box in which the counter-shaft is journaled, and showing the adjusting screw-bolt inserted through the bight of the yoke and bearing 35 upon the exterior of said box. Fig. 2 is a transverse section of the rack-standard and yoke, taken through the line $x-x$ on Fig. 1.

Letters Patent of the United States No. 310,928, dated January 20, 1885, granted to 40 me for an improvement in mechanism for raising and lowering harvesting-machines, shows and describes a sample of the type of raising-and-lowering mechanism in which the windlass-shaft is inserted through the 45 center of the drive-wheel, and is provided with a gear for engaging the teeth of a curved rack-standard bolted to the harvester-frame. The said rack-standard is also provided with a V-shaped yoke, the bight of which is hung

directly upon the box in which the counter-shaft has its bearing.

In my present invention I employ a similar rack-standard composed of the two curved members f , f' , united at the top and bottom, and provided with the usual bolt-holes, 1 2 3 4, for the reception of the bolts by which the rack-standard is fastened to the main frame of the harvester, and provided with the usual curved rack, f' . The yoke is composed of the converging arms f^2 and f^3 , the meeting 60 of which forms the bight f^4 , which embraces the box e . A boss, 6, cast upon the convex side of the bight of the yoke, is perforated to receive the adjusting screw-bolt 7, provided with the nuts 8 and 9, respectively upon the 65 inner and outer sides of the bight, and serving as jam-nuts to securely fasten the bolt 7 in the position to which it may be adjusted. The inner end of the bolt 7 bears, as will be seen, upon the exterior of the box e .

By loosening the bolts 8 and 9 the set-screw 7 may be turned back or forth, as may be required, to effect the adjustment of the box e relatively to the segmental rack f' , so that the rack will be concentric with the counter-shaft c' , having its bearing in the box e . When such adjustment has been effected, the tightening of the jam-nuts 8 and 9 securely fastens the adjusting-bolt 7, and the permanent maintenance of the proper relation between the counter-shaft c' and the rack f' is thereby secured.

I claim as my invention—

1. In a harvester-frame, a metallic yoke and means for adjusting the same, whereby the proper distance is maintained between the center of the drive-wheel and the center of the counter-shaft through which power is transmitted from the drive-wheel.

2. A metallic rack-standard and yoke, substantially such as herein described, provided with suitable bolt-holes for the reception of the bolts by which it is secured to the frame of the harvester, and adapted to embrace the box e , in which the counter-shaft c' has its bearing, and provided with the adjusting screw-bolt 7, inserted through the bight of the yoke for the purpose of centralizing the journal

formed in the box *e* relatively to the curved rack *f*.

3. The curved metallic rack *f'*, formed upon a suitable standard adapted to be bolted 5 to the frame of a harvester and cast or otherwise formed in one piece with a yoke the bight of which is provided with an adjusting screw-bolt, substantially such as described, in com-

bination with box *e*, which affords the bearing for the counter-shaft through which power is transmitted from the driving-wheel gear.

JOHN F. APPLEBY.
